UNITED STATES PATENT OFFICE

JOSEPH ARTHUR BOLDUC, OF MONTREAL, QUEBEC, CANADA, ASSIGNOR TO AUTOMOBILE "LOCK-ALARM" CORPORATION, OF NEW YORK, N. Y., A CORPORATION OF NEW YORK

ALARM APPARATUS

Application filed February 26, 1926. Serial No. 90,732.

This invention relates to alarm apparatus, and more particularly to such an apparatus as is disclosed in my co-pending application for patent Serial No. 80,403, filed January 11, 1926, and which is particularly designed for application to motor vehicles for the purpose of apprising the owner and others that an attempt is being made by an unauthorized person to operate the vehicle.

10 In the operation of the invention described in the application just referred to, when the ignition switch or other switch operated by a movable part of the vehicle is closed, the horn or other audible alarm device is sounded, and even though the switch may again be opened, the circuit of the sounding device remains closed so that the operation of said device will continue. The noise incident to this continuous sounding of the alarm device 20 has met with some objection, and it is the purpose of my present invention to provide a very simple addition to the device disclosed in my pending application whereby the circuit of the alarm device may be automatically broken independently of the switch and said circuit then again closed so as to cause the alarm device to be intermittently operated.

It is another object of my invention to 30 provide an automatic means for intermittently breaking and making the circuit of the alarm device which is of such construction that the time interval between the periods of operation of the device may be varied as desired.

With the above and other objects in view, the invention consists in the improved alarm apparatus and in the form, construction and relative arrangement of its several parts as 40 will be hereinafter more fully described, illustrated in the accompanying drawings, and subsequently incorporated in the subjoined claims.

In the drawings, wherein I have illustrated one simple and practical embodiment of the invention, and in which similar reference characters designate corresponding parts throughout the several views,—

Figure 1 is an elevation, the housing or 50 casing for the several parts being shown in

section and the mechanism illustrated in proper position to sound the alarm upon closing of the switch;

Fig. 2 is a horizontal sectional view taken substantially on the line 2—2 of Fig. 1; 55

Fig. 3 is a sectional view taken substantially on the line 3—3 of Fig. 1, and

Fig. 4 is a diagrammatic view showing the normal condition when the vehicle is being operated by the owner with the primary or 60 ignition circuit closed.

Referring in detail to the drawings wherein I have illustrated the several essential parts of the apparatus enclosed within a suitable housing or casing 3 which is adapted to 65 be mounted in any convenient location upon the under side of the vehicle dashboard, as shown more particularly in Fig. 4 of the drawings. The wires or other conductors 1 and 2 respectively, may be connected in any 70 suitable manner with a plurality of suitably constructed switches connected with various parts of the vehicle, as for instance the engine hood, doors, brakes or spare tire lock. Thus, should any attempt be made to disturb 75 the normal condition of the parts, the switch will be closed.

Suitably mounted in one wall of the box 3 and insulated therefrom the spaced binding posts 4, 5, 6 and 7 respectively, are arranged. A conductor 8 extends from the post 4 to the ignition apparatus of the vehicle and is subsequently grounded. A conductor 9 is connected to the post 5, to the battery 10 and hence to the ground. This conductor 9 has 85 interposed therein the ignition switch indicated at 11 and to said conductor at opposite sides of the switch 11, the lines 1 and 2 are joined.

An audible signalling or alarm device such 90 as an electrically operated horn 12 is connected to the binding post 7 and to the ground as at 13. A conductor 14 extending from the post 6 is joined to the conductor 9 between the battery 10 and the ignition switch 11. 95

Within the box 3 an electromagnet 16 is mounted. A bracket 17 is also fixed to one wall of the box and is provided with an angularly disposed apertured lug 18, Figure 4, 100

which slidably guides a manually operable part 19 extending through an opening 20 in one side wall of the casing or housing 3. The outer end of this part 19 has bearing contact against the short arm 21 of an L-shaped lever 22 which is pivoted as at 23. The other arm of this lever is engaged by the inner end of a push button 24 suitably mounted in the dashboard of the vehicle.

Within one end of the casing or housing 3 spaced plates 25 and 26 respectively, are pivotally mounted for swinging movement and are yieldingly urged in one direction by the springs 27. A similar plate 28 is also pivotally mounted between the plates 25 and 26 and carries a rod or bar 29 engaged at its ends with one side of the plates 25 and 26 to swing the latter against the action of the springs 27, the ends of said bar being suitably insulated from said plates.

The plate 25 adjacent one edge is provided with a shoulder 30 for a purpose which will be later pointed out, while the plate 26 is formed at its free end with an arm or extension 31 having an insulating material 32 secured upon one side thereof. This arm is adapted for engagement in a notch or recess 34 formed in an upstanding flange 33 on the part 19 so that the shoulders at the opposite ends of this recess will engage the edges of the metal arm 31.

To the binding post 4 a resiliently yieldable conductor bar 35 is connected and is provided with a contact 36 to engage a similar contact 37 on a rigid conductor plate 38 connected with the binding post 5. As will be later described, the part 19 has its end opposed to an insulating block 39 on the conductor 35 and is adapted to move said conductor and break the connection between the contacts 36 and 37 whereby the ignition circuit will be opened independently of the switch 11.

Spaced binding posts 40 and 41 are mounted within the housing 3, the post 40 having a connection 42 with the conductor 38 and a connection 43 with the winding of the electromagnet 16. The post 41 is connected by a wire 44 with the hinged or pivoted plate 26. A contact piece or screw 46 is engaged by a resilient metal strip 47 to which an armature 48 is fixed at one of its ends. The other end of this armature is provided with an angularly extending arm 49, the purpose of which will presently appear.

A conductor 50 extends from the binding post 6 and has an angularly disposed resiliently movable end portion 51, the terminal of which is positioned in the angle formed by the armature 48 and the arm 49 thereof and is provided with an insulating sleeve 52. This angular end 51 of the conductor has a part 53 fixed thereto adapted to cooperate with the plate 25 and being normally engaged

with the insulation 54 on the face of this plate. This plate 25 is connected with binding post 7 by the wire or other conductor 55. The resiliently movable part of the conductor 50 is also provided with an extension 56 adapted to engage a contact member 57, fixed to the end of the conductor 38, but is normally out of engagement therewith.

A plate 58 is suitably fixed within the housing 3 and upon a stud shaft 59 fixed in this plate the large ratchet wheel 60 is rotatably supported. The teeth of this ratchet wheel are engaged by a suitable spring pressed pawl 61 to prevent retrograde rotation of said ratchet. A second smaller ratchet wheel 62 is journalled upon the stud shaft 63 fixed in plate 58 and the teeth thereof are also engaged by spring pawl 64. The arm 49 of armature 48 carries a spring pawl 65 which also cooperates with the teeth of the ratchet wheel 62 and in the movement of the arm 49 in one direction, imparts a rotative movement to said ratchet wheel. This ratchet wheel 62 carries a pin or stud 66 which, in each revolution of said wheel engages one of the teeth of the ratchet wheel 60 and thus imparts a step by step rotative movement to the latter wheel.

Upon the under side of the plate 58 a slide bar 67 is suitably mounted and has a lug or finger 68 on one end projecting through an opening 69 in said plate. This lug is adapted to cooperate with one end of a lever 70 pivoted intermediate of its ends as at 71 upon the plate 58, and positioned between the ratchet wheel 60 and the plate. The other end of said lever is inwardly curved and is adapted to be engaged by a pin or stud 72 projecting from the under side of the ratchet wheel 60. The slide bar 67 at its other end bears against an insulating sleeve 73 on one end of an arm 74 fixed to the plate 25. This slide bar is retracted and yieldingly held in the position shown in Fig. 1 of the drawings by suitable coil springs 75.

The part 19 is normally urged in one direction by a spring 76 in which position of said part the contacts 36 and 37 are engaged as seen in Fig. 4 to close the ignition circuit. For the purpose of operating the plates 25 and 26 to permit the return of said part to its normal position and the breaking of the alarm circuit, I provide a pin tumbler lock indicated at 77 suitably mounted in the dashboard of the vehicle and having its barrel 115 connected by a rod 78 with the intermediate pivoted or hinged plate 28, as in my prior application.

Any number of other switches may be connected in the circuit illustrated in Fig. 4 of the drawings, and I have therein indicated conductors 79 for one such switch connected with the lines 1 and 2.

In the normal operation of the vehicle equipped with my alarm apparatus, the parts 130

are in the relative positions shown in Fig. 4 of the drawings with the contacts 36 and 37 engaged with each other while the insulation 32 on plate 26 is engaged with the part 19 and the extension 53 of conductor 50 is engaged with the insulation 54 on plate 25. Thus, when the ignition circuit is closed in the usual way, the current flows from battery 10 through conductor 9 to the post 5 and along the conductor 38 through contacts 36 and 37 and conductor bar 35 and post 4 and hence through conductor 8 to the ignition apparatus and from the latter to the ground.

When the owner or operator of the vehicle leaves the same unattended, he merely pushes upon the button 24 and thereby rocks lever 22 to force the part 19 inwardly. The end of this part bearing against the lug 39 disengages contact 36 and contact 37 and thereby breaks the ignition circuit independently of the switch 11. At the same time, the notch 34 in the flange 33 of said part 19 moves beneath the arm 31 of the plate 26 and this arm is urged downwardly into said notch by the spring 27 so that the opposite end edges of the notch are engaged with the side edges of said arm. The parts are now in the position shown in Fig. 1 of the drawings. Should the ignition switch 11 now be closed in the attempt by one contemplating the theft of the machine to operate the same, the current will flow from the battery along the conductor 9 to the post 5 through conductor 38 to post 40, through conductor 43 and the windings of the magnet 16 to the screw 46 along strip 47 which is connected to post 41 and hence along conductor 44 to plate 26 through part 19 to bracket 17 which is grounded through the wall of the casing or housing. Thus a circuit energizing the magnet 16 is completed whereupon the armature 48 is attracted and this armature engaging the insulating sleeve 52 pulls the resilient end portion of the conductor 50 thereby disengaging the extension 53 from insulation 54 of plate 25 and positioning the end of said extension in line with the recess or notch 30 of said plate so that the spring 27 may force the plate downwardly to engage the edge of said notch with the extension 53. At the same time extension 56 of the conductor 50 is engaged with contact 57. It will be noted that there is sufficient space between sleeve 52 and extension 53 to permit of the vibration of armature 48 while said conductor is held in the circuit closing position above described. The contact 46 remains engaged with the strip 47 so that the armature 48 continues to vibrate while at the same time a circuit is closed from the battery through conductor 14, post 6, conductor 50, plate 25, conductor 55, post 7 and hence to the grounded horn 12 or other sounding device. Should one of the other switches connected in the lines 1 and 2 be closed, the same circuit would then be closed through

conductor 38, contact 57 and conductor 50. As the armature 48 vibrates, ratchet wheel 62 is rotated by the pawl 65, and a step by step movement is imparted to the ratchet wheel 60 until pin 72 on said wheel engages the end 70 of lever 70 and by the camming action thereon rocks said lever to move the slide bar 67 against the action of spring 75. The end of this slide bar bearing on sleeve 73 moves the plate 25 independently of the other plate 26 75 which remains in circuit closing position, and thereby breaks the connection between the extension 53 of the conductor 50 and said plate 25 whereupon the conductor 50 returns to its normal position, thereby breaking the 80 circuit last described so that the operation of the alarm device 12 is stopped.

The alarm device will remain silent until pin 72 moves off of the curved end of the lever 70 whereupon spring 75 retracts the slide 67, 85 thus permitting the plate 25 under the action of spring 27 to be again engaged with the end 53 of conductor 50, thereby closing the circuit and operating the alarm device. In this manner, said alarm device will be intermittently operated. The intervals between operations of the alarm device may be increased or decreased as desired by changing the ratios of the ratchet wheels 60 and 62 with an increase or decrease in the number of 90 teeth of the wheel 60, and also by changing the location of pin 72 with respect to the axis 59 of the ratchet wheel 60 so that this pin will remain in contact with the curved end of lever 70 for a greater or a less length of 95 time.

When the lock barrel 77 is operated so as to disengage plate 26 from the flange 33 of the part 19, and of course simultaneously disengage part 25 from the end 53 of conductor 50, the operating circuit for the alarm device 12 and the circuit for the electromagnet 16 is definitely broken, said part 19 being returned to normal position by spring 76 and engaged with the insulation 32 on the plate 26 while contact 36 again engages contact 37 to close the break in the ignition circuit.

From the foregoing description, considered in connection with the accompanying drawings, my present improvements will be clearly and fully understood. It will be seen that by a very simple addition to the apparatus as shown in my prior application, the operating circuit for the alarm device is intermittently broken or interrupted. The alarm apparatus will therefore, be more effective in attracting attention and frustrating possible theft of the motor vehicle while at the same time the noise incident to the operation of the device is reduced.

While I have herein shown and described a practical and satisfactory embodiment of my invention, it is nevertheless, to be understood that the same results might possibly be 130

obtained in other alternative structural forms thereof, and I therefore, reserve the privilege of resorting to all such legitimate changes in the form, construction and relative arrangement of the several parts as may be fairly embodied within the spirit and scope of the invention as claimed.

I claim:

1. In a theft alarm system for automobiles, an alarm circuit, a switch in said circuit including a member biased for movement in one direction to circuit opening position, and latching means for holding said member in closed circuit position against said bias, a vibratory member, electromagnetic means included in a normally open circuit for vibrating said member, inter-engaging means between the first named member and said vibrating member for moving said biased member to latched position and to thereafter permit the free vibration of said vibrating member, and means including a ratchet and pawl mechanism operated by said vibrating member for releasing said latch member after a predetermined number of vibrations of said vibratory member.

2. In a theft alarm system for automobiles, an alarm circuit, a switch in said circuit including a member biased for movement in one direction to circuit opening position and latching means for holding said member in closed circuit position against said bias, a vibratory member, electromagnetic means included in a normally open circuit for vibrating said member, said biased means disposed in the path of movement of said vibratory member for moving said biased member to latched position out of the path of the vibratory member upon the initial movement of the latter and thereafter permit the free vibration of the vibratory member, and means operable by the vibratory member for releasing said latch member after a predetermined number of vibrations of said vibratory member.

In testimony that I claim the foregoing as my invention, I have signed my name hereto.

JOSEPH A. BOLDUC.
